ICE HANDLING MACHINE

Application filed November 7, 1929. Serial No. 405,384.

This invention relates to ice handling machines and, among other objects, aims to provide a portable automatic machine which is so constructed and arranged as to turn a block of ice from one face onto an adjacent face.

In the drawings,

Fig. 1 is a plan view of one embodiment of the invention;

Fig. 2 is a side elevation of the same;

Fig. 3 is a wiring diagram showing the control circuit;

Fig. 4 is a longitudinal sectional view of the machine shown in Fig. 1;

Fig. 5 is an end elevation of the same; and

Fig. 6 is a diagrammatic sectional view showing the cradle, the conveyor chain and drive therefor.

For various reasons, it is almost universal practice to handle ice blocks by sliding or conveying them on their narrow longitudinal faces or edges. However, it is frequently desirable to stand them on end as when they are placed in the day storage room, that is, a room designed to hold only a day's supply of ice. By storing the ice on end, the capacity of the room is greatly increased, so that a room which is large enough to hold an average day's supply of ice stored on edge will generally hold a maximum day's supply when the ice is stored on end. As the ice cakes weigh 300 to 400 lbs., it is not an easy matter to turn them on their ends to store them, or to lower them on edge when they are to be moved from the storage room. The present invention provides a machine which is adapted to turn the cakes up on one end or to take ice stored on end and turn it to lie on edge, and which is portable so that the work may be performed at different places in one plant.

Referring particularly to the drawings, the preferred form of the invention is there shown embodied in a portable machine, which comprises a frame 10, having an oscillatory cradle 11, into which a block of ice is placed. When the block reaches its proper position in the cradle, an electric circuit is automatically closed (in a manner to be described) causing motor driven mechanism to

swing the cradle through approximately 90°, when the block is automatically discharged from the machine, after which the cradle automatically swings back to receive another block.

In the present instance, the frame 10 is substantially rectangular in shape and formed of structural angles 12, 13 and 14 extending longitudinally of the frame, and having cross brace members 15, 16, 17 and 18. A bottom plate 19 extends between the side members 12 and 14 and between the intermediate braces 16 and 17, being welded or otherwise secured to these members to strengthen the frame. The cradle 11 is shown as having a bottom 20, an end 21 and a pair of substantially triangular sides 22 and 23, all preferably made of heavy gauge sheet metal and rigidly secured together with the sides extending beyond the bottom and end. The bottom and end may be braced by means of structural angles secured to the outer faces of the bottom and end.

The cradle 11 is pivotally mounted between the frame angles 13 and 14 by means of a shaft 24 which extends through the extended cradle sides 22 and 23 just outside the junction of the bottom 20 and end 21 and is journaled in bearings 25 secured to the beams 13 and 14. When in position to receive a block of ice to be upended, the cradle is in the position shown in full lines in Figs. 2, 4 and 6, that is, supported on the bottom plate 19 of the frame, with the bottom 20 of the cradle in substantially horizontal position a short distance above the floor on which the machine rests.

In order to get the ice from the floor into the bottom of the cradle, an inclined skidway 26 (Figs. 1 and 4) is provided between the beams 13 and 14 and extends rearwardly from the floor level at the front end of the machine to the level of the cradle bottom just ahead of the cradle. After an ice block on edge has been slid end first and up the skidway and into the cradle, the cradle is swung upwardly and rearwardly, by mechanism to be later described, to substantially vertical position (see dotted lines, Fig. 4) until its end 21 is supported by the bottom

plate 19 in substantially horizontal position and spaced above the floor level. A second skidway 28 extends rearwardly from a point just in rear of and on the level of the end, 5 when it is in the above-mentioned position, to the floor level at the rear end of the machine.

In order that the ice block may be automatically discharged from the cradle in upended position, a pair of track members 29 (Fig. 4) 10 are provided having upper converging inclined surfaces 30 and 31, the surfaces 30 forming a continuation of the rear skidway 28. The end 21 of the cradle is provided 15 with openings 32 (Figs. 4 and 5) to permit the upper portions of the tracks to project above the level of the end 21 when the cradle is in vertical position. The apices 33 of the surfaces 30 and 31 are so located that as the 20 cradle approaches its vertical position, these apices project through the end 21 and engage the lower end of the ice cake in front of its center of gravity. Upon further movement of the cradle, the cake is caused to tilt rearwardly until its lower end engages the surfaces 30 and the skidway 28 (see dotted position in Fig. 4) when the cake will slide 25 down the skidway and onto the floor in upended position. The cradle is then returned to horizontal position to receive another cake, as will be described.

Herein, the means for swinging the cradle consists broadly of a fixed abutment on the cradle adapted to be engaged by a movable element, preferably carried by a chain. See 30 Fig. 6. A bracket 34 is rigidly secured to the side plate 23 of the cradle and is provided with rearwardly extending portions having a vertical slot 35 (Fig. 1) and an intersecting 35 transverse slot 36 (Fig. 6) providing a pair of spaced upper arms 37 and a pair of spaced lower arms 38. An endless sprocket chain 39 is trained over lower and upper sprockets 40 and 41 respectively, and around a drive 40 sprocket 42; another sprocket 43 being located near the drive sprocket 42 to cause the chain to contact with approximately one-half the teeth of the drive sprocket. The sprocket 43 may be adjustable (not shown) to take up 45 play in the chain.

The sprockets 40 and 41 are journaled in a support 44 (Fig. 2) which is mounted on the main frame 10 adjacent to the side 23 of the cradle. As shown in Fig. 6, the front portion 50 of the lower sprocket 40 extends partially into the slot 35 between the arms 37, while the lower portion is slightly below the central part of the slot 36. Between the sprockets 40 and 41 the chain 39 is constrained to move in an arcuate path, by means of a guide track 45, whose outer edge, over which the chain slides, is concentric with the pivot shaft 24. The chain is provided with a special link 46 having a pair of laterally extending lugs 47 adapted to enter the slot 36

and engage the arms 37 and 38. When the cradle is in horizontal position, the link 46 is in the lower or horizontal flight of the chain 39 and to elevate the cradle, the drive sprocket 42 is rotated in a clockwise direction. The lugs 47 then enter the slot 36 and engage the arms 37, and upon further movement of the chain, the cradle is swung upwardly to vertical position, as indicated in dotted lines, Fig. 6. While moving between the sprockets 40 and 41, the lugs engage both the arms 37 and the arms 38, thereby practically locking the cradle to the chain.

When the cradle is in vertical position, the upper portion of the sprocket 41 extends partially into the slot 35 between the arms 38 while the rear portion is slightly in rear of the central part of the slot 36. If the chain continues to move, the lugs 47 move downwardly out of the slot 36, so that no damage will be done. In order to return the cradle to horizontal position, it is only necessary to reverse the direction of the chain, that is, by driving sprocket 42 in a counterclockwise direction. The lugs move upwardly into the slot 36, engaging first the arms 38 and then both pairs of arms 37 and 38, causing the cradle to be lowered to horizontal position. When the cradle reaches that position, the lugs 47 leave the slot 36 and enter the lower flight of the chain.

The drive sprocket 42 may be operated in any desired manner, but it is herein shown as being operated through the medium of a gear reduction transmission unit 48, operably connected to an electric motor 49. See Figs. 1, 2 and 5.

In order to start the motor automatically when a block of ice is placed in the cradle, a switch 50 (Figs. 1 and 4) is mounted on the bottom 19 and arranged so as to be normally open with the end of a lever arm 51 projecting through and above the bottom 20 near the end 21, so as to be engaged and depressed by an ice block when the block reaches its proper position in the cradle. The switch 50, upon being closed, closes a standard magnetic switch 52 (see Fig. 3) closing the circuit to the motor, which drives the chain 39 in a clockwise direction. A geared limit switch 53 (Fig. 2) is operatively connected to the transmission 48 by a sprocket chain 54 and is so arranged that as the cradle approaches its vertical position, it breaks the circuit of the magnetic switch 52, which in turn breaks the motor circuit. The switch 52 upon breaking the motor circuit operates a time relay 55, which, after a short period of time, reverses the motor by means of the reversing magnetic switch 52^a, causing the motor 49 to move the chain in a counterclockwise direction, thereby returning the cradle to horizontal position. When the cradle reaches this position, the switch 53 breaks the circuit in the solenoid of the switch 120

52^a, which in turn breaks the motor circuit. When the frame is to be lowered, the operator does not operate the time relay 55 and iterator may depress both levers 60 and 63 until another cake of ice is placed in the cradle. By including a change over switch 56 in circuit with the time relay 55, the relay lever 60 to raise, lowering one corner of the frame may be caused to operate to reverse the motor frame to the floor. Similar action will lower the frame when the cradle is in horizontal position, and after the other three corners. The cradle will then stop in vertical position, thereby making the machine adaptable for lowering ice, as will be described.

To lower suspended ice cakes to one edge, the tracks 29 are removed, and similar tracks 26 be pushed into the cradle when it will be automatically turned to another face and discharged through openings 57 in the plate 19, so as to project through the cradle. From the foregoing it will be seen that the machine may be readily raised, moved about and lowered to rest on the floor in any desirable location. A block of ice may then be pushed into the cradle when it will be automatically turned to another face and discharged from the machine, the cradle then being lowered to the floor. Switch 50 is also moved, automatically returning to receive another block so as to be actuated by the cakes. The ice block is pushed up the skidway 28 into the cradle, and even this, in some locations, may be done by a power-operated conveyor, or a gravity ice run. The chain 39 then moves in a counterclockwise direction, lowering the cradle. Obviously, the present invention is not restricted to the particular embodiment thereof shown and described. Moreover, the cradle is automatically discharged from the machine by the above-mentioned tracks (not of herein shown and described). It is not indispensable that all the features shown, sliding by gravity down the skidway 26 onto the floor. After a short period of time the cradle returns to vertical position to receive another suspended block.

While the machine could remain stationary at all times, it is desirable to make it portable, so that it may be located near the point where the ice is to be stored. This is done by pivoting the cradle at its end, because when moved about on end, ice falls to the cradle between its ends; and it is liable to fall over and break or injure the person handling it. Therefore, an abutment to swing the cradle by power on its pivot axis, as shown in Figs. 1 and 2, the machine is provided with two pairs of supporting wheels, one pair being swiveled 58 and located one at either side near the front end; an endless chain drive in a plane of the machine, and the wheels 59 of the cradle; mechanism for reversibly driving said chain; an abutment fixed to the cradle between its ends; and means fixed to the chain for engagement with the abutment connected at one end to a bracket 61 and rigidly secured to the frame 10. The arrangement is such that when the frame rests flat on the floor, the free ends of the levers 60 extend upwardly at an inclination, as shown in Fig. 4. A latch rod 62 is slidably mounted on each lever, having one end pivotally connected to a spring-pressed trip lever 63, the other end being adapted to engage the corner of the frame. To raise the frame, the operator depresses the free end of one of the levers, and the wheel axle serves as a pivot pin for the lever, so as to swing the cradle by power in either direction on its pivot axis. This procedure is followed with each of the other three levers, when the frame is raised. This procedure is followed with each of the other three levers, when the frame will be supported on the rollers, and due to the caster wheels 58 the frame may be readily moved about.

What I claim is:

1. A machine of the class described comprising, in combination, a pivoted cradle; a point where the ice is to be stored. This is done by pivoting the cradle at its end, because when moved about on end, ice falls to the cradle between its ends; and it is liable to fall over and break or injure the person handling it. Therefore, an abutment to swing the cradle by power on its pivot axis, as shown in Figs. 1 and 2, the machine is provided with two pairs of supporting wheels, one pair being swiveled 58 and located one at either side near the front end; an endless chain drive in a plane of the machine, and the wheels 59 of the cradle; mechanism for reversibly driving said chain; an abutment fixed to the cradle between its ends; and means fixed to the chain for engagement with the abutment connected at one end to a bracket 61 and rigidly secured to the frame 10. The arrangement is such that when the frame rests flat on the floor, the free ends of the levers 60 extend upwardly at an inclination, as shown in Fig. 4. A latch rod 62 is slidably mounted on each lever, having one end pivotally connected to a spring-pressed trip lever 63, the other end being adapted to engage the corner of the frame. To raise the frame, the operator depresses the free end of one of the levers, and the wheel axle serves as a pivot pin for the lever, so as to swing the cradle by power in either direction on its pivot axis. This procedure is followed with each of the other three levers, when the frame is raised. This procedure is followed with each of the other three levers, when the frame will be supported on the rollers, and due to the caster wheels 58 the frame may be readily moved about.

2. A machine of the class described comprising, in combination, a cradle pivoted at one end to swing vertically; an endless chain lying in a vertical plane adjacent one side of the cradle; mechanism for reversibly driving said chain; an abutment fixed to and projecting beneath a fixed abutment 64 on the side of the cradle which is adjacent the frame. To raise the frame, the operator depresses the chain; and means fixed to the chain presses the free end of one of the levers; and engageable with the abutment, irrespective of the direction in which the chain is driven, so as to swing the cradle by power in either direction on its pivot axis. The wheel axle serves as a pivot pin for the lever, so as to swing the cradle by power in either direction on its pivot axis. This procedure is followed with each of the other three levers, when the frame is raised. This procedure is followed with each of the other three levers, when the frame will be supported on the rollers, and due to the caster wheels 58 the frame may be readily moved about.

3. A machine of the class described comprising, in combination, a cradle pivoted at one end to swing vertically; an endless chain lying in a vertical plane adjacent one side of the cradle; mechanism for reversibly driving said chain; an abutment fixed to and projecting beneath a fixed abutment 64 on the side of the cradle which is adjacent the frame. To raise the frame, the operator depresses the chain; and means fixed to the chain presses the free end of one of the levers; and engageable with the abutment, irrespective of the direction in which the chain is driven, so as to swing the cradle by power in either direction on its pivot axis. The wheel axle serves as a pivot pin for the lever, so as to swing the cradle by power in either direction on its pivot axis. This procedure is followed with each of the other three levers, when the frame is raised. This procedure is followed with each of the other three levers, when the frame will be supported on the rollers, and due to the caster wheels 58 the frame may be readily moved about.

4. A machine of the class described comprising, in combination, a cradle pivoted at one end to swing vertically; an endless chain lying in a vertical plane adjacent one side of the cradle; mechanism for reversibly driving said chain; an abutment fixed to and projecting beneath a fixed abutment 64 on the side of the cradle which is adjacent the frame. To raise the frame, the operator depresses the chain; and means fixed to the chain presses the free end of one of the levers; and engageable with the abutment, irrespective of the direction in which the chain is driven, so as to swing the cradle by power in either direction on its pivot axis. The wheel axle serves as a pivot pin for the lever, so as to swing the cradle by power in either direction on its pivot axis. This procedure is followed with each of the other three levers, when the frame is raised. This procedure is followed with each of the other three levers, when the frame will be supported on the rollers, and due to the caster wheels 58 the frame may be readily moved about.

- jecting from the side of the cradle which is adjacent the chain; means fixed to the chain and engageable with the abutment, irrespective of the direction in which the chain is driven, to swing the cradle by power in either direction on its pivot axis; said abutment being so constructed and arranged and the chain being so guided that when the cradle is upright, and also when it is horizontal, the means fixed to the chain will move out of contact therewith, so that breakage will not occur even if the chain continues to move for some distance after the cradle has reached either limit of movement.
5. A machine of the class described comprising, in combination, a cradle pivoted to swing through an arc of about 90° ; a power-actuated mechanism for swinging the cradle in either direction on its pivot axis; a track member having an apex intermediate its ends, and so placed relative to the cradle as to receive a cake of ice on its apex, which provides a fulcrum for the cake; the track member having an inclined surface extending from the apex to its outer end; and a skidway substantially alined with said inclined surface and so placed as to receive a cake of ice as it slides down the track member.
6. A machine of the class described comprising, in combination, a cradle comprising an end, a bottom and two sides, all of which are dimensioned so as to receive a commercial ice cake; said cradle being pivoted near its end so as to swing through an arc of about 90° ; a track member located adjacent the end of the cradle and about on a level with the bottom of cradle when said bottom is horizontal; said track member having two oppositely inclined top surfaces meeting in an intermediate apex providing a fulcrum on which an ice cake may rock; the cradle having an opening in its end to permit its end to swing down substantially to a horizontal position without interference with the track member; the ice cake, after rocking on the track member, sliding down an inclined surface thereof and being discharged from the machine.
7. A machine of the class described comprising, in combination, a cradle pivoted at one end; a power-actuated endless chain lying in a plane adjacent the cradle; a bracket fixed to one side of the cradle near its free end and having a vertical slot and an intersecting transverse slot providing a pair of spaced upper arms and a pair of spaced lower arms; one link of the chain having a pair of laterally extending lugs adapted to enter the transverse slot and engage the upper and lower arms aforesaid; the chain thus swinging the cradle about its pivot axis in one direction or the other.
8. A machine of the class described comprising, in combination, a cradle pivoted at one end; a power-actuated endless chain lying in a plane adjacent the cradle; a bracket fixed to one side of the cradle near its free end and having a vertical slot and an intersecting transverse slot providing a pair of spaced upper arms and a pair of spaced lower arms; one link of the chain having a pair of laterally extending lugs adapted to enter the transverse slot and engage the upper and lower arms aforesaid; the chain thus swinging the cradle about its pivot axis in one direction or the other; the slots and lugs being so constructed and arranged that if the chain continues to move in either direction after the cradle has reached the limits of its movement, the lugs move out of the slots and away from the bracket, so that no parts may be broken.
9. A machine of the class described comprising, in combination, a cradle so constructed and arranged as to swing through an arc of about 90° ; an electric motor; mechanism interposed between the motor and cradle to swing the cradle; a motor circuit including reversing magnetic switches, a switch located adjacent the cradle and adapted to close the motor circuit as soon as an ice cake is in position on the cradle, a limit switch actuated by the motor to stop the swinging of the cradle in both directions, and a master switch.
10. A machine of the class described comprising, in combination, a cradle so constructed and arranged as to swing through an arc of about 90° ; an electric motor; mechanism interposed between the motor and cradle to swing the cradle; a motor circuit including reversing magnetic switches, a switch located adjacent the cradle and adapted to close the motor circuit as soon as an ice cake is in position on the cradle, a limit switch which is operated by the motor to break the motor circuit as the cradle reaches its limits of movement; a time relay which effects a pause in the cradle movement when in upper position, and a master switch.
11. A machine of the class described comprising, in combination, a frame; a cradle constructed and arranged to receive a cake of ice and turn it through 90° ; an electric motor; and electric control means in the circuit of the motor adapted to automatically start and stop the cradle and to automatically bring the cradle back to its initial position, and remain in that position with the motor at rest until another cake of ice is placed on the cradle.
12. A machine of the class described comprising, in combination, a cradle so constructed and arranged as to swing through an arc of about 90° ; an electric motor; mechanism interposed between the motor and cradle to swing the cradle; a motor circuit including reversing magnetic switches, a switch located adjacent the cradle and adapted to close the motor circuit as soon as an ice cake is in position on the cradle, a limit switch

which operates to break the motor circuit as the cradle reaches its limits of movement; a time relay which effects a pause in the cradle movement when in upper position; a change-over switch in circuit with the time relay so as to make the relay operate when the cradle is in horizontal position, and a master switch.

13. A machine of the class described comprising, in combination, a cradle pivoted to swing through an arc of about 90°; a power-actuated mechanism for swinging the cradle in either direction on its pivot axis; and a track member having an apex intermediate its ends, and so placed relative to the cradle as to receive a cake of ice on its apex.

14. A machine for up-ending ice cakes and the like comprising, in combination, a frame; three vertical sprockets on the frame; an endless chain trained over said sprockets; a lug secured to the chain; a cradle mounted to oscillate through an arc of about 90° and having means projecting therefrom for engagement by the lug during its travel between two of the sprockets; means for guiding and supporting that portion of the chain which extends between said two sprockets; and power-actuated means for driving said chain.

30 In testimony that I claim the foregoing as my own, I have hereto affixed my signature.

STANLEY H. DURBIN.
